UNITED STATES PATENT OFFICE.

ELLIS T. SILVIUS, OF INDIANAPOLIS, INDIANA, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,160,538.

Specification of Letters Patent.

Patented Nov. 16, 1915.

Original application filed May 4, 1909, Serial No. 493,922. Divided and this application filed January 4, 1913. Serial No. 740,176.

To all whom it may concern:

Be it known that I, ELLIS T. SILVIUS, a citizen of the United States, residing at Indianapolis, in the county of Marion and 5 State of Indiana, have invented certain new and useful Improvements in and Relating to Filing Appliances, of which the following is a specification.

This invention relates to filing appliances 10 adapted for the receiving and holding of papers, paper slips, bills and the like, whereby they may be readily and accurately filed, inspected and removed at will.

The application is a division of my application filed May 4, 1909, Serial No. 493,922, issued October 13, 1914, in Patent No. 1,113,698.

For the purpose of illustration, I have, in the accompanying drawings, shown and 20 herein described one form of apparatus embodying my invention.

Figure 1 is a front elevation of the improved filing appliance arranged in proper position for use, the lower portion of the 25 case or cabinet being broken away. Fig. 2 is a vertical sectional view of the cabinet with some of the leaves in normal positions and some in prone positions, as on the line A in Fig. 1 or near the inner side of the left 30 hand side of the case and partially broken away, the leaves being shown in side elevation. Fig. 3 is a fragmentary vertical sectional view as at the inner side of the back of the case looking forward. Fig. 4 is a 35 fragmentary vertical sectional view on the line B—B in Fig. 1 with all the leaves in their normal positions and inclosed by the case. Fig. 5 is a fragmentary vertical sectional view approximately on the line F in 40 Fig. 1 with the leaves in various positions and illustrating the relative arrangement of the leaf springs. Fig. 6 is a fragmentary horizontal sectional view taken at the right hand side of the register, as on the plane of 45 the line D in Fig. 2. Fig. 7 is a plan view of the normal bottom of the leaf inverted. Fig. 8 is a fragmentary sectional view of a leaf as on the line E—E in Fig. 7. Fig. 9 is a perspective view of a ratchet wheel 50 for adjusting the tension of the leaf springs. Fig. 10 is a perspective view of the head block and a guide rod of the leaf springs with which the ratchet wheel cooperates. Fig. 11 is a perspective view of the leaf

follower constituting a support or stop for 55 the upright leaves to limit rotative movements of the leaves rearward.

In the construction the improvement comprises a desk part having sides 1 and 2 and a front 3, the rear portion of the desk part 60 having a case erected thereon having two sides 4 and 5, and a back 6 joined to the sides and extending down to form the back of the desk part, a rail 7 extending between sides 1 and 2 at the lower forward portions 65 of the sides 4 and 5, and a floor 8 extending from the rail rearward to the back 6. A door 9 is connected by hinges 10 to the forward side of the rail 7 and normally lies on the sides 1 and 2 to form a top for the 70 desk part, and may swing to an upright position against the fronts of the sides 4 and 5 to inclose the leaves when desired. The case is provided with a cover or lid 11 that is connected by hinges 12 to the back 6, the 75 under side of the cover being provided with a suitable catch 13 adapted to engage a projection 14 on the inner side of the side 5 of the case to hold the cover in closed position, a suitable lock 15 being provided for locking the door 9 to the cover 11, so as to prevent access to the accounts or bill slips on the leaves. The top is provided with a pair of suitable props 16 and 17 that are adapted to engage supporting devices 18 and 19 for 85 holding up the cover when the appliance or register is in use as in Fig. 2. The case, however, may be otherwise constructed if desired.

A base 20 for the bill holding leaves is 90 mounted removably on the floor 8 and has its rear side inserted under fingers 21 which are secured to the floor, the forward part of the base being held firmly on the floor by a suitable button or catch 22 that will permit 95 of the base being removed from the floor when desired. A pair of pivoting stands 23 and 24 are secured on the top of the forward portion of the base for supporting all the bill holding leaves.

The leaves may be variously constructed in detail and they comprise a forward frame 25, intermediate frames as 26, 26', 26'', and a rear frame 27, each frame having a hinge-bar 28 which is the bottom portion of the 105 frame when in its normal upright position, and the ends of the hinge-bar are provided with projecting ears 29 and 30 which have

suitable pivots or hinge rods thereon for connecting the frames one to another as a group. Each hinge-bar 28 has a pair of head blocks 31 and 32 mounted thereon opposite to the ears and secured removably preferably by means of screws 33. The head blocks have guide rods 34 and 35 connected thereto that extend through the ears 29 and 30, so that their outer ends constitute pivots 5 or hinge-rods 36 and 37 for the frame. The hinge-rod is fitted closely in the head block and in the ear and is rigid in either the ear or the head block, preferably in the latter. The head-blocks are provided with ratchet teeth 38 that extend toward the ears. Two ratchet-wheels 39 and 40 are provided for each leaf frame, and they have each a suitable number of ratchet teeth 41 adapted to engage the teeth 38, the wheels having sockets 42 in their peripheries for turning them, and axle bearings 43 to receive the guide rods on which they are rotatively mounted. Each leaf frame is provided with two balancing-springs 44 and 45, one on each of the 10 two guide rods, and each coiled about its guide-rod, and having arms 46, one each entering or engaging a ratchet-wheel, and the opposite end of the springs having arms 47 and 47', one arm on each spring. The arms 25 47 and 47' of the springs of the forward frame engage clips 48 and 49 that are secured to the base 20, and the similar arms of the springs of all the other leaf frames rearward of the forward frame engage the hinge-rods of the next adjacent forward frame, as and for the purposes hereinbefore explained. Each leaf frame hereinbefore mentioned has two pivots 36 and 37 and the pivots of the foremost frame 25 are mounted 30 in the pivoting stands 23 and 24, and the arms 47 and 47' being anchored enable the springs to exert their energy toward holding the leaf frame upward or toward the rear of the case, and, of course, may be adjusted, so as to lift the leaf from the prone position. Each leaf frame, except the rearmost one, is provided with a pair of arms 50 and 51 that extend transversely to the plane of the frame, being rearward when the frame is upright, and the arms may extend at any suitable angle, preferably at right angles to the plane of the frame. The pivots of the frame 26 are mounted in the arms of the frame 25 and similarly the pivots of each succeeding frame are mounted in the arms of the adjacent forward frame, so that the foremost frame is pivotally supported and supports all the other frames collectively, each one of the frames exerting 40 a gravity force at the ends of the arms of the next forward frame which acts to move the upper ends of the frames rearward when the frames are somewhat near to vertical positions. The springs that are mounted on the frame 26 act to hold that frame upright, 50

and when moving upright do not disturb the action of the frame 25. The springs on the frame next above or behind the frame 26 tend likewise to raise the leaf, and the arms 27 and 27' of the springs being in engagement with the guide rods of the frame 26 have little influence toward disturbing the action of the frame 26, but tend in a slight degree to raise the frame 26, so that as will be seen while the springs tend to raise the leaf frames they do not exert their force toward holding down the prone leaves. In some cases it may be desirable and is permissible to dispense with the balancing springs on all the intermediate leaves and the foremost leaf, but it is preferable to employ the springs on the foremost leaf since it is clear that the leaves when upright will so remain by the force of gravity if prevented from falling forward, but the springs are usually desirable for causing the leaves to move up to their normal positions quickly.

As above-mentioned the leaves may be variously constructed in detail and preferably the foremost leaf comprises a shutter 90 52 arranged at the forward side of the frame 25 and connected to the hinge-bar 28 of the frame by hinges 53 and 53', a suitable latch 54 being provided for detachably fastening the free end of the shutter to the free end of the leaf frame, the inner side of the shutter being provided with a suitable number of bill clamps 55 for holding memorandum slips or papers other than the regular bill slips. The frame 25 has also a plate 56 attached thereto completing the leaf proper and to which a suitable number of bill clamps 57 are mounted on the rear side thereof for holding sales-bills, the plate 56 being preferably midway between the front 95 and rear sides of the frame. The intermediate frames each comprise a plate as 58 attached thereto midway between the forward and rear sides thereof, and the rearmost frame 27 has a plate 59 attached to the rear side thereof, the plates of the intermediate leaves having bill clamps 57 thereon, and the plate of the rearmost leaf having bill clamps 60 on the inner side thereof. Preferably the inner or upper side of the door 9 has a cushion 61 to be engaged by the forward leaf frame 25 when in prone position, and the base 20 has a cushion 62 thereon to be engaged by the rearmost frame when the leaves are in normal upright positions, the cushions serving to prevent noise in action. It will be understood that when the leaves are in upright positions they may be in exact perpendicular planes or may all lean slightly rearward at an angle if desired, and obviously when in prone position they may be either exactly horizontal or may be slightly inclined with their forward or free ends slightly lower than their pivoted ends, as may be desired.

In order to prevent the upright leaves from swinging rearward beyond the desired normal position, the rearmost leaf is provided with a suitable device for limiting the pivotal movement of the leaf rearward, the device being movable with the rearmost leaf and detachable therefrom. The device and its connections preferably comprise two guide bars 69 and 70 that are attached to the inner sides of the sides 4 and 5 of the case and extend approximately from the back 6 upward toward the forward edges of the sides of the case, the guide bars having guide grooves 69' and 70' therein respectively. A follower comprises a carriage having two sides 71 and 71' and a cross-bar 72 connected to the two sides, the sides having vertical guide grooves 73 and 73' in the inner sides thereof respectively. The carriage is provided with axles 74 and 74' on which are wheels or rollers 75 and 75' running in the guide grooves 69' and 70', and the sides have arms 76 and 76' thereon that extend upward and are provided at their upper ends with rollers 77 and 77' that engage the rear side of the rearmost leaf. The pivots of the rearmost leaf extend into the guide grooves 73 and 73', so that vertical movement may occur as between the rearmost leaf and the carriage of the follower during irregular or variable movements of the rearmost leaf as it describes arcs of circles either about the axis of the pivots of the foremost leaf or the pivots of either of the other leaves, and therefore as the rearmost leaf moves upward and forward or in reverse direction it is constantly in the same vertical angle by reason of being in engagement with the rollers on the arms of the follower. Of course, if desired the rollers can be dispensed with, so that direct contact would be made by the rear leaf against the arms. The follower as will be seen is moved by means of the rearmost leaf, but its path is controlled by the guide bars on the case. When it is desired to omit the balancing springs above described or in case an auxiliary spring is desired the rearmost leaf frame 27 has a projection 78 thereon to which is hooked a spring 79 that is connected to the cross-bar 72 of the follower and so strained that the spring will exert its force to draw the rear leaf to an upright position and hold it against the arms of the follower, the spring permitting the leaf to be drawn down to prone position.

80 indicates a locking member having a journal 81 rotatably mounted on the base 20. The locking member is provided with a finger 83 which is adapted to engage a latch plate 84 secured to the hinge bar 28 of the rearmost frame. The locking bar 80 normally lies on the base 20 when not in use, (see Fig. 1), and when swung upward pivotally it engages the rear side of the rear-

most leaf to prevent rearward movement of the leaf relatively to the base, while the finger 83 prevents the base from moving relatively to the leaves about the pivots of the foremost leaf, so that when removed 70 from the case the series of leaves will stand upright as a rectangular pack.

When desired a plate 88 is connected by hinges 89 to the inner side of the back 6 and has another plate 90 connected thereto by 75 hinges 91, the plates normally leaning against the back 6, and are convenient on which to place index sheets or delinquent sheets commonly used in the system.

It will be apparent that the case as an 80 inclosure for the leaves may be dispensed with if desired, so that the case sides need be only sufficiently high to support the inclined guide-bars 69 and 70, the back of the case and the cover of course being omitted 85 in construction, and thus apparatus may be considerably cheapened to supply the needs of the smaller user.

In practical use the apparatus may be operated essentially as must result from the 90 construction hereinbefore described, and it will be observed that the series of bill holding leaves and their supporting base may be readily inserted into the case of the register or cabinet or removed therefrom, and it will 95 be apparent that when the leaves and base are removed from the case they will occupy but little more space than that required for the leaves alone. The index sheets will be so arranged that they can not be scrutinized 100 by the over-curious, and memorandum charge slips or partially filled orders may be conveniently filed temporarily on the inner side of the shutter 52. Miscellaneous bills or accounts of casual credit customers may 105 be kept on the rearmost leaf while the accounts of the regular customers will be kept on the other leaves. In small stores or where the register is not used constantly the door 9 may be closed and locked to prevent 110 tampering with accounts during temporary absence of the proprietor. After the door is unlocked and drawn down to prone position the cover 11 may then be unlatched and raised so that the leaves may be operated. 115

During the movement of all the leaves together from upright to prone positions the pivots of the rearmost leaf as also those of the other leaves would follow concentric circles about the pivots of the foremost leaf 120 and the follower would be drawn along with the rearmost leaf. If one or more of the foremost leaves are drawn forward the pivotal axis of the rearmost leaf will follow a curve that is eccentric to the axis of the pivots of the foremost leaf, and then if all the remaining leaves be drawn forward the pivots of the rearmost leaf will follow another curve that is eccentric to the axis of the pivots of the foremost leaf and arrive at 130

the position that it should occupy when all the leaves are prone, so that the motions may be various, depending on the number of leaves that may be drawn forward at a time, and in all cases the pivots of the rearmost leaf will move vertically with respect to the follower at different points of movement of the leaves forward or backward, but in as much as the vertical movements as between 5 the rearmost leaf and the follower are with sliding or flexible connections vertically, the vertical angles of the leaves remain the same at all times, which is a convenience to the merchant or attendant in that he may become accustomed to reach to a certain vertical plane at all times to have access either to the foremost leaf or to either one of the other leaves when drawn forward after those preceding have been drawn to prone 15 positions. Other results and advantages of operation will from the foregoing description be understood.

To those skilled in the art of making apparatus of the class described, many alterations in construction and widely differing embodiments and applications of my invention will suggest themselves, without departing from the spirit and scope thereof.

My disclosures and the description herein 30 are purely illustrative, and are not intended to be in any sense limiting.

What I claim is:—

1. A plurality of leaves pivotally supported normally in upright positions, the foremost one of the leaves being movable only pivotally to and fro and the remaining leaves being movable pivotally and also bodily to and fro, one or more of the leaves having each a balance spring mounted on the under side 35 thereof provided with tension-adjusting devices and such being carried to and fro by the bodily movable leaves.

2. In a filing appliance, the combination of a series of leaves having connecting devices between them permitting pivotal movements relative to each other, the said leaves operating when one or more of the leaves are reclined to move the remaining upright leaves forwardly, means for supporting the 45 front leaf of the series, and a balance device carried by each leaf.

3. In a filing appliance, the combination of a series of leaves having connecting devices between them permitting pivotal movements relative to each other, the said leaves operating when one or more of the leaves are reclined to move the remaining upright leaves forwardly, means for supporting the 55 front leaf of the series, and a balance spring carried by each leaf.

4. In a filing appliance, the combination of a series of leaves having connecting devices between them permitting pivotal move-

ments relative to each other, the said leaves operating when one or more of the leaves are 65 reclined to move the remaining upright leaves forwardly, means for supporting the front leaf of the series, and a balance spring carried by each leaf, one arm of the said spring bearing against an abutment on an 70 adjoining leaf of the series.

5. A plurality of leaves having each a pivotal axis and connected one to another to move rotatively and operating, when one or more of the leaves are reclined, to move 75 the remaining leaves forwardly, all the leaves excepting one of the end leaves of the series having each a spring guide thereon and a spring on the guide, the spring having an arm anchored to the leaf and also an 80 arm coöoperating with an adjacent one of the leaves at the pivotal axis thereof, with a pivotal support for one of the end leaves.

6. An account register including a base, a series of normally upright leaves of which 85 the foremost one thereof is pivotally mounted on the base, all the leaves being rotatably supported and connected one to another, each leaf having a head block attached to the under side thereof that is provided with 90 ratchet teeth, a guide rod on the head block, a wheel on the guide rod having ratchet teeth engaging the teeth of the head block, and a spring on the guide rod having an arm engaging the wheel and having also an 95 arm suitably anchored.

7. In a filing appliance, the combination of a base, a series of leaves pivotally mounted on the base, a head block carried by each leaf, a guide rod mounted in the head block, 100 a spring carried by the guide rod, a spring tension adjusting device to which one end of the spring is connected for winding and unwinding the said spring, and locking means interposed between the head block and the 105 adjusting device for locking the latter in adjusted positions.

8. A credit-accounting register including a plurality of leaves having each a pair of projections on an end thereof, a pair of ears 110 secured detachably on the end opposite the projections, rods secured rigidly in the projections and extending therethrough and also into the ears, the outer ends of the rods forming pivots adjacent the projections, 115 springs on the rods and engaging the ears and having projecting arms, means for supporting the pivots, and means for anchoring the arms of the springs.

In testimony whereof I affix my signature, 120 in the presence of two witnesses.

ELLIS T. SILVIUS.
